Primary Examiner — Jennifer L Rempfer*Assistant Examiner* — Emily A Caven(74) *Attorney, Agent, or Firm* — NOD Law PC(57) **CLAIM**

The ornamental design for a pet toy, as shown and described.

DESCRIPTION

FIG. 1 is a perspective view of the pet toy;

FIG. 2 is a left side view of the pet toy;

FIG. 3 is a right side view of the pet toy;

FIG. 4 is a top plan view of the pet toy; and,

FIG. 5 is a bottom plan view of the pet toy.

The shade lines in the Figures show contour and not surface ornamentation.

The evenly spaced broken lines in the drawings illustrate portions of the pet toy that form no part of the claimed design.

1 Claim, 5 Drawing Sheets(56)
